US00D763858S

(12) **United States Design Patent**
Fluckiger et al.

(10) **Patent No.:** **US D763,858 S**
(45) **Date of Patent:** **** Aug. 16, 2016**

(54) **PROTECTIVE COVER FOR AN INPUT DEVICE**

(71) Applicant: **Logitech Europe S.A.**, Lausanne (CH)

(72) Inventors: **Jean-Marc Fluckiger**, Tsuen Wan (HK); **Chun-Wei Su**, Taipei (TW); **Yibo Shao**, Tsuen Wan (HK)

(73) Assignee: **Logitech Europe S.A.**, Lausanne (CH)

(***) Term: **15 Years**

(21) Appl. No.: **29/539,292**

(22) Filed: **Sep. 11, 2015**

(51) LOC (10) Cl. **14-02**

(52) U.S. Cl.

USPC **D14/440**; D14/447

Primary Examiner — Cynthia Underwood

(74) Attorney, Agent, or Firm — Kilpatrick Townsend & Stockton LLP

(57) **CLAIM**

The ornamental design for a protective cover for an input device, as shown and described.

DESCRIPTION

FIG. 1 is a perspective view of a protective cover for an input device with a disclaimed input device showing our new design;

FIG. 2 is a perspective view thereof;

FIG. 3 is a top view thereof;

FIG. 4 is a bottom view thereof;

FIG. 5 is a front view thereof;

FIG. 6 is a back view thereof;

FIG. 7 is a left view thereof;

FIG. 8 is a right view thereof.

FIG. 9 is a perspective view of a protective cover for an input device with a disclaimed input device showing our new design;

FIG. 10 is a perspective view thereof;

FIG. 11 is a top view thereof;

FIG. 12 is a bottom view thereof;

FIG. 13 is a front view thereof;

FIG. 14 is a back view thereof;

FIG. 15 is a left view thereof; and,

FIG. 16 is a right view thereof.

The broken lines in the drawings depict environmental subject matter only and form no part of the claimed design.

1 Claim, 6 Drawing Sheets
